UNITED STATES PATENT OFFICE

HAROLD E. HALLENBECK, OF HUDSON, NEW YORK, ASSIGNOR TO GIFFORD-WOOD COMPANY, OF HUDSON, NEW YORK, A CORPORATION OF NEW YORK

TROLLEY BUCKET INSTALLATION

Application filed May 9, 1930. Serial No. 451,038.

This invention relates to trolley buckets and, among other objects, aims to provide a trolley bucket installation with a counter-weighted cable for retarding fall of the bucket should the main hoist cable break, and also aims to arrange the cables in such a way that the bucket has a smoother operation and is under better control at most stages of the operation.

Referring to the accompanying drawing showing more or less diagrammatically the preferred embodiment of the invention, the single figure is an elevation of a part of a trolley bucket installation, the means for effecting traverse of the bucket being omitted.

Because of the heavy expense of repeated handling and long distance hauling of coal and other heavy materials, there has been a distinct trend in recent years toward the establishment of "neighborhood" yards, that is to say, yards located in various sections of a city for the storage and retail selling of coal, coke, gravel, sand and the like. The more modern yards are especially designed to be run with a minimum of labor, being served from a railroad siding and so arranged that the coal or other material may be dumped from the railroad car and carried by a traversing hoist bucket to storage bins, from which wagons or trucks are easily loaded by gravity. See in this connection Fig. 1 of the pending application of W. H. Towne, Serial No. 146,890 and Fig. 2 of the pending application of H. V. Harding, Serial No. 144,121, both of which have been assigned to the assignee of the present application.

An installation of the character described saves not only the handling cost but also reduces breakage of the coal to a minimum, obviates the losses which occur when different materials in adjacent piles become more or less commingled, protects the material against the weather and hence makes it possible to handle coal and the like in very cold weather without thawing (as the bins are protected from the weather), speeds up deliveries as much as 100% or more, thus cutting down the investment necessary for trucks and the labor costs of delivery, and ef-

fects other important savings unnecessary to mention.

In practice, however, certain operating difficulties occasionally develop, among them being failure of the hoisting cable, which is due to internal friction from the constant bending over sheaves and which is also due to the occasional kinking or twisting of the cable which may take place when the bucket is hoisted after discharging its load on the pile. At such times, the hoist cable may be twisted through many turns because of rotation of the bucket, which necessarily twists the hoist cable between the trolley sheaves and the sheave on the bail of the bucket. Such twisting and kinking is very destructive to the cable and may cause it to break immediately.

In accordance with the invention, I minimize the possibility of damage to the bucket and other parts and injury to employees resulting from breakage of the hoist cable by employing a second cable which is connected with a counterweight in a novel manner and which cooperates with the power actuated hoist cable, as will be explained below, to effect novel and useful results, particularly making the operation of the bucket smoother and minimizing tipping of the bucket, which would cause the twisting heretofore mentioned.

Referring particularly to the drawing, there is shown a trolley bucket 1, preferably of the construction shown in the Bennett Patent 1,741,123. The bucket 1 is suspended from a hoist cable 2 by means of a sheave 3 pivoted to the bail 4 of the bucket. The hoist cable 2 is dead-ended as at 5 and is guided by sheaves 6, 7, preferably all suspended from the monorail 9, or its supports (not shown). The other end of the hoist cable 2 is wrapped around the hoist drum 10, which is driven by an electric motor, not shown, either automatically or manually controlled. The monorail 9 extends the length of the installation over the bins or silos in which the material is stored. It provides a track for the trolley 11, said trolley being suspended from hangers 12 which are secured to the axles of rollers 13 which run along

the opposite lower flanges of the monorail 9.

The parts so far described are standard and form no part of the present invention except as they cooperate with the novel elements to be described and claimed.

5 The second cable, indicated at 14, supports a heavy counterweight 15 of any desired construction, preferably by means of a sheave 16 mounted on the upper end of 10 the counterweight. The cable 14 is secured at one end to the hoist drum 10 and is wrapped around said hoist drum in a direction opposite to the one in which the cable 2 is wrapped. Guide sheaves 17 and 18 are 15 provided for the cable 14 between the counterweight 15 and the hoist drum 10. Preferably the sheave 17, together with a similar guide sheave 19, is mounted on a bracket 20 which is supported by a hanger 21 upon the 20 monorail 9. Preferably, the hanger 21 and the bracket 20 are offset relative to the monorail so that the trolley 11 may travel along that part of the monorail without interference with the sheaves 17 and 19 or their supporting members.

25 The cable 14 passes around a sheave 22 at one end of the monorail, preferably on the same axis as the sheave 6 but having a smaller diameter than sheave 6. From the sheave 22 the cable 14 passes around a sheave 23 rotatably mounted on the trolley 11, thence around the sheave 24 which is on the axis of the bucket sheave 3, being likewise pivoted to the bucket bail, thence around sheave 25 on the trolley and to the dead-end 26. The hoist cable passes around trolley sheaves 27 and 28 which are on the same axes as the sheaves 23 and 25 respectively, but which are of smaller diameter, as shown. On the other hand, the bucket sheave 3 for the hoist cable is of larger diameter than the bucket sheave 24 about which the cable 14 passes.

30 From the above it will be seen that the cables 2 and 14 pass around four pairs of sheaves, namely, the sheaves 6 and 22 at one end of the monorail, the sheaves 23 and 25 at one end of the trolley, the sheaves 3 and 24 on the bucket, and sheaves 27 and 28 on the other end of the trolley. In each pair, the sheaves are of unequal diameter and the cables alternate in passing around the smaller and larger of the several pairs of sheaves. Thus, at one end of the monorail, the cable 2 passes around the larger sheave 6, but passes around the smaller sheave 27 on the trolley, around the larger sheave 3 on the bucket, and around the smaller sheave 28 at the other end of the trolley. The peculiar arrangement of sheaves, while not indispensable, is a desirable one, as it minimizes twisting of the cables, especially if the sheaves on the trolley and bucket be spaced apart a short distance so as to provide, in effect, four spaced lines supporting the bucket on the trolley. Preferably, the

sheaves of each pair differ in diameter by two inches or so.

Heretofore, counterweights have been used in connection with trolley bucket systems because they necessitate less power in operating and also insure smoother operation and far better control of the bucket when descending with a load. However, known arrangements of counterweighted cables have been entirely different from the one described in this application and have imposed heavy stresses on the cables and also on the drum. According to the present invention, the counterweight is effective directly on the bucket itself as well as on the drum, and thus relieves some of the load on the hoist cable and on the drum. In one particular installation, the counterweight cable reeving described in this application would relieve a stress of 1000 pounds on each cable and will 75 relieve the drum of 2000 pounds stress. This will permit the use of a smaller hoist cable with the same factor of safety and the use of a smaller hoist cable increases the longevity 80 of the cable because, as is well known, the life 85 of a cable is determined largely by the amount of twisting and bending to which it is subjected; a cable of smaller diameter being less injured by bending over a sheave of a given size than is a larger cable. Furthermore, 90 lessening the stresses imposed on the hoist drum will minimize bearing troubles and will even make possible the use of smaller and less expensive bearings.

95 The described cable reeving provides a 100 means for suspending the bucket from a counterweight should the main hoist cable fail. An empty bucket cannot fall with the described arrangement, but it will slowly descend, as the weight of an empty bucket is 105 greater than the effective weight of the counterweight. A full bucket will descend much more rapidly in case the hoist cable breaks, but its descent will not be accelerated as in the case of free gravity fall and very little damage will occur. However, usually the hoist 110 cable breaks with an empty bucket, because it is the empty bucket which twists the cable, and it is the twisting which is hardest on the cable and most frequently breaks it.

115 The particular manner of suspending the bucket by means of two cables passing over three pairs of sheaves, two of which pairs are on the trolley, will minimize twisting of the bucket after discharge of the load. The invention also makes for smoother action of the bucket at the time of discharge, minimizing tipping of the bucket because the counterweight will straighten up the bucket as soon as it starts to tip or lean sidewise on the pivots of the bail. The elimination of tipping 120 of the bucket is most desirable, as such tipping usually starts twisting of the cable.

125 Traverse of the bucket along the monorail is effected by means of a traverse cable 29,

the opposite ends of which are made fast to the ends of trolley 11, as shown, and which is driven by a motor driven drum as shown in Figs. 1 and 2 of the above-identified application of H. V. Harding.

Obviously, the present invention is not restricted to the particular embodiment thereof herein shown and described. A number of changes may be made, as for instance, securing the counterweight to the end of cable 14 instead of dead-ending it to the monorail. Such an arrangement, while within the scope of some of the claims, is much less desirable because it would necessitate a counterweight 10 twice as heavy as in the illustrative arrangement, and the counterweight would have to travel twice as far, in fact, as far as the bucket itself.

What I claim is:—

1. In a trolley bucket installation, the combination of a bucket; a trolley; two cables for supporting the bucket from the trolley; both cables being secured to a fixed member at one end; a counterweight acting on one cable to maintain a tension thereon so as nearly to overcome the weight of the empty bucket; and a hoist drum; both cables being wrapped around said hoist drum, but in opposite directions.

2. In a trolley bucket installation, the combination of a track; a trolley movable along the track; a bucket carried by the trolley; two cables for supporting the bucket from the trolley; both cables being separately dead-ended at one end of the track; two pairs of sheaves on the trolley for said cables; a pair of sheaves on the bucket for said cables; guiding sheaves for both cables supported adjacent the track; a counterweight supported by a sheave from one of the cables; and a hoist drum about which both cables are wrapped, but in opposite directions.

3. In a trolley bucket installation, the combination of a bucket; a trolley; two cables for supporting the bucket from the trolley; a pair of sheaves of unequal diameter at each end of the trolley, the sheaves of each pair being spaced apart laterally of the trolley but rotating about the same axis; a pair of sheaves 45 of unequal diameter supported on the bucket; one of the cables being passed about the larger sheave at each end of the trolley and about the smaller sheave on the bucket; the other cable being passed about the smaller sheave at each end of the trolley and about the larger sheave on the bucket; a counterweight 50 suspended from one of said cables; and a hoist drum about which one end of each cable is wrapped, but in opposite directions.

4. In a trolley bucket installation, the combination of a track; a trolley movable along the track; a bucket carried by the trolley; two cables for supporting the bucket from the trolley; both cables being separately dead-ended at one end of the track; two

pairs of sheaves on the trolley for said cables; a pair of sheaves on the bucket for said cables; guiding sheaves for both cables supported adjacent the track; a counterweight supported by a sheave from one of the cables; and a hoist drum about which both cables are wrapped, but in opposite directions; the sheaves on the trolley being spaced apart laterally as well as longitudinally of the trolley and the sheaves on the bucket being likewise spaced apart laterally, so that the two cables provide four spaced bights supporting the bucket and lessening the tendency of the bucket to turn about a vertical axis under certain operating conditions.

5. In a trolley bucket installation, the combination of a bucket having a bail; two cables supporting the same; power-actuated means for automatically paying out one of the cables as the other is reeled in; a counterweight 85 suspended from one of the cables; both cables passing under sheaves carried by the bail of the bucket and over sheaves carried by the trolley; both cables being made fast at one end to a fixed member.

6. In a trolley bucket installation, the combination of a bucket having a bail; a pair of sheaves on the bail rotating about the same axis but spaced apart laterally; a trolley; two pairs of sheaves supported on the trolley and spaced longitudinally thereof, the sheaves of each pair rotating on the same axis and spaced apart laterally of the trolley the same distance as the sheaves on the bail of the bucket; a pair of cables passing around said sheaves; and power-driven means to wind up said cables alternately as the drum is rotated in opposite directions; the arrangement being such that as the bucket descends, the counterweight ascends, and vice versa.

In testimony that I claim the foregoing as my own, I have hereto affixed my signature.
